(57) **CLAIM**

The ornamental design for an electric machine as shown and described.

DESCRIPTION

FIG. 1 is a front side view of electric machines drive mount.

FIG. 2 is a rear side view thereof.

FIG. 3 left side view thereof.

FIG. 4 is a right side view thereof.

FIG. 5 is a top side view thereof.

FIG. 6 is a bottom side view thereof.

FIG. 7 is a front isometric view thereof; and,

FIG. 8 is a rear isometric view thereof.

1 Claim, 7 Drawing Sheets
